UNITED STATES PATENT OFFICE.

JACOB J. NICHOLS AND WILLIAM S. MCLEWEE, OF NEW YORK, N. Y.,
ASSIGNORS TO BRADLEY & HUBBARD MANUFACTURING COMPANY, OF
WEST MERIDEN, CONN.

DESIGN FOR A LAMP-FOUNT.

SPECIFICATION forming part of Design No. 11,939, dated August 10, 1880.

Application filed June 9, 1880. Term of patent 7 years.

To all whom it may concern:

Be it known that we, JACOB J. NICHOLS and Wm. S. MCLEWEE, of New York, in the county of New York and State of New York, have invented a new Design for a Lamp-Fount; and we do hereby declare the following, when taken in connection with the accompanying drawings and the letters of reference marked thereon, to be a full, clear, and exact description of the same, and which said drawings constitute part of this specification, and represent, in—

Figure 1, a side view; Fig. 2, a top view.

This invention relates to a design for lamp-fount; and it consists in the shape of the fount, as shown in the accompanying illustrations.

At the top, in horizontal plane, the fount is

in form of an ellipse, as seen in Fig. 2, and from the largest dimensions at the top it contracts in curved lines longitudinally, as seen in Fig. 1, and transversely, as seen in Fig. 3. 20

The usual provision is made at the top for the collar, and at the bottom for attachment to the socket.

We claim—

The design for lamp-fount, substantially as 25 shown, consisting in the form thereof.

J. J. NICHOLS.
W. S. MCLEWEE.
